UNITED STATES PATENT OFFICE.

FRANK L. IRWIN AND JOHN E. TESSEYMAN, OF COLUMBUS, OHIO, ASSIGNEES TO THE
RALSTON STEEL CAR COMPANY, OF COLUMBUS, OHIO, A CORPORATION OF OHIO.

HOPPER-CAR.

1,075,571.

Specification of Letters Patent.

Patented Oct. 14, 1913.

Application filed May 26, 1911. Serial No. 629,710.

To all whom it may concern:

Be it known that we, FRANK L. IRWIN and JOHN E. TESSEYMAN, citizens of the United States, residing at Columbus, in the county of Franklin and State of Ohio, have invented certain new and useful Improvements in Hopper-Cars, of which the following is a specification.

Our invention relates to improvements in hopper cars, and herein is applied to a twin hopper car having a center sill hood, and consists especially in forming the cross hood in such a manner that it may be securely joined to the center sill hood and the sides of the car, and is strongly reinforced. In this construction, preferably the bottom line of the center girder and that of the hopper are in the same horizontal plane, and the bottom line of the side girder plates is in a horizontal plane between the top and bottom of the center girder construction; this construction of car we deem to have great advantages in the matter of strength and correctness of design, whereby a saving of material is effected and the reinforcement of the various parts is more readily and appropriately provided for.

Essentially the cross hood embodied in this application is made up of sloping sides, one being adapted to abut against the other at the apex, and a continuous ridge or cover piece is applied to the apex and extends from side to side of the car, and is secured to the inside side stake at its ends. The cross hood is also supported by a bracing angle member extending from side to side of the hood and being secured thereto.

In the drawings which are hereto attached and hereby made a part of this specification, Figure 1 is a vertical longitudinal section through one end of a car on a line between the center sill and side of the car, having our improvements therein; Fig. 2 is a vertical transverse section through one end of the car along the line A—A of Fig. 1; Fig. 3 is a vertical transverse section through the cross hood showing the reinforcement thereof and the manner of connecting the same to the inside side stakes. Fig. 4 is a top plan view showing the cross hood broken away at the ends and the manner of applying the cross hood to the center sill hood; Fig. 5 is a vertical transverse section through Fig. 4 along the line B—B.

In the drawings, 1 is the center girder construction, formed, in this instance, of parallel channels with their flanges inwardly disposed; 2 is the end slope sheet, 3 designates the side of the car, 4 the center sill hood, traversing the car longitudinally, having sloping sides with flanges 5 and 6 formed at their lower edges and overlapping the vertical webs of the center sill channels and being riveted thereto at 7 and 8. The center sill hood near the end of the car is firmly joined to the end slope sheet 2 along the line shown generally at 9, and in a well known way at its other end the center sill hood is joined to the cross hood, by having the flanges 10 and 11 formed thereon through which rivets, as at 12 and 13, are inserted, thereby securing the hoods together.

The cross hood is formed of the inclined or sloping sheets 14 and 15 which meet at their upper ends at 16, one abutting against the other; the lower edges of the cross hood sheets lie in a horizontal plane with the lower edges of the center sill, whereas the lower edges of the side frame of the car lie in a more elevated horizontal plane, as appears clearly in Fig. 2. The cross hood is connected to the center sill hood 4 as noted above, and the ridge or cover member 17 is applied to the apex of the cross hood and extends from side to side of the car as appears especially in Fig. 2, and is secured to the cross hood by means of rivets as appears at 18. The ridge member 17 is likewise secured to the outwardly inclined flanges 28 at the lower end of the inside side stake 24 by means of rivets as appears at 26, the attachment being similarly effected on the opposite side of the car, all of which appears in Fig. 2. Referring to Fig. 3, the rivet 26 secures together the flange 28 of the inside side stake 24, the ridge member 17, and the sloping side 15 of the cross hood, thereby strongly reinforcing the cross hood construction, the reinforcing construction being similarly made at the opposite side of the cross hood by rivet 25 passing through members 17, 27, and 14.

The cross hood is united to the center sill hood in the manner above pointed out, and also there are provided the angle members 29 and 30 which are secured to the outer face of a channel of the center girder and are securely riveted thereto, and also riveted

to the inner faces of the cross hood sheets, whereby the ends of the cross hood sheets abutting against the center sill are firmly secured thereto. A further bracing member 35 extends from one side to the other of the cross hood and is preferably an angle member with its flanges bent at the ends as appears at 36 and 37, and rivets 38 and 39 pass therethrough and through the sloping sheets 14 and 15 of the cross hood. Therefore, the cross hood construction provided herein is reinforced by the ridge or cover member 17 passing over the whole length of the cross hood, is also reinforced by connection with the inside side stakes, also by the flange members connecting the center sill hood therewith, by the angle members applied to the center sill, and by the angle member extending across the cross hood and being secured to the sloping sheets thereof, whereby a most effective bracing and reinforcing construction is provided. Further, the angle members 41 and 42 are applied to the lower edges of the cross hood sheets and are secured thereto by rivets as appears at 43. In Fig. 4 rivets 40 and 40^a are shown which secure together the cross hood sheet 14 and the end of the angle brace 35. In this construction the ridge member 17 is seen to be applied to the apex of the cross hood from side to side of the car continuously and is secured thereto throughout its length, and at its ends is likewise secured to the wide inwardly projecting flanges of the inside side stakes. At about the middle point, said member 17 bears upon the center sill hood 4. This manner of construction imparts very great strength to the cross hood and gives strong reinforcement thereto and to the sides of the car. Further, it is apparent that it is immaterial whether

sheet 14 or 15 is the overlapping one at the apex.

What we claim is:—

1. In a hopper car having a center sill, a cross hood formed of sloping oppositely inclined sheets secured at their ends to the center sill and the sides of the car and abutting along their upper edges, and a ridge member extending continuously from side to side of the car and applied to the apex of said cross hood.

2. In a hopper car having a center sill, a cross hood formed of sloping oppositely inclined sheets secured at their ends to the center sill and the sides of the car and abutting along their upper edges, and a ridge member extending continuously from side to side of the car and applied to the apex of said cross hood, and an inside side stake applied at its lower end to said ridge member and secured thereto and to said cross hood sheets.

3. In a hopper car having a center sill, a cross hood formed of sloping oppositely inclined sheets secured at their ends to the center sill and the sides of the car and abutting along their upper edges, and a ridge member extending continuously from side to side of the car applied to the apex of said cross hood to reinforce said cross hood longitudinally, and a bracing member disposed within said cross hood and united at its ends to the sides of said cross hood to afford reinforcement thereto transversely.

In testimony whereof we affix our signatures in the presence of two witnesses.

FRANK L. IRWIN.

JOHN E. TESSEYMAN.
